DESIGN FOR A CASE FOR A MEASURING TAPE

Adolf W. Keuffel, Montclair, N. J., assignor to Keuffel & Esser Company, Hoboken, N. J., a corporation of New Jersey

Application April 26, 1935, Serial No. 56,573

Term of patent 14 years

To all whom it may concern:

Be it known that I, Adolf W. Keuffel, a citizen of the United States and residing in the town of Montclair, county of Essex, and State of New Jersey, have invented a new, original, and ornamental Design for a Case for a Measuring Tape, of which the following is a specification, reference being had to the accompanying drawing, forming a part thereof.

Figure 1 is a plan view showing the top face of the case.

Figure 2 is a plan view of the case looking from below.

Figure 3 is a fragmentary, transverse, sectional view taken in the plane indicated by the line 3—3 of Figure 1 looking in the direction of the arrows to show particularly the elevated and depressed portions of the design.

I claim:

The ornamental design for a case for a measuring tape, as shown and described.

This specification signed this 22nd day of April, 1935.

ADOLF W. KEUFFEL.
